(57) **CLAIM**

The ornamental design for a material property measurement device, as shown and described.

DESCRIPTION

This invention was made with Government support under Grant Number 19134080 awarded by the National Science Foundation. The Government has certain rights to this invention.

FIG. 1 illustrates a rear, top, and right side perspective view of a material property measurement device according to the present invention.

FIG. 2 illustrates a front, bottom, and left side perspective view of the material property measurement device of FIG. 1. FIG. 3 illustrates a top elevation view of the material property measurement device of FIG. 1.

FIG. 4 illustrates a bottom elevation view of the material property measurement device of FIG. 1.

FIG. 5 illustrates a right side elevation view of the material property measurement device of FIG. 1.

FIG. 6 illustrates a left side elevation view of the material property measurement device of FIG. 1.

FIG. 7 illustrates a rear elevation view of the material property measurement device of FIG. 1; and,

FIG. 8 illustrates a front elevation view of the material property measurement device of FIG. 1.
